UNITED STATES PATENT OFFICE.

CHARLES G. MALLIET, OF JERSEY CITY, NEW JERSEY.

DESIGN FOR A BADGE, PIN, &c.

SPECIFICATION forming part of Design No. 17,983, dated December 27, 1887.

Application filed October 17, 1887. Serial No. 232,643. Term of patent 24 years.

To all whom it may concern:

Be it known that I, CHARLES G. MALLIET, a citizen of the United States, residing at No. 816 Grand street, Jersey City, in the county of Hudson and State of New Jersey, have invented and produced a new and original Design for Badges, Pins, and Charms, of which the following is a specification, reference being had to the accompanying drawing, forming part thereof.

The figure is a front view of my new design.

The leading features of my design consist of an ornament shaped as shown in the drawing, the base being a Maltese cross in shape, from the center of which projects an elk's head erect, with horns and ears, &c., surrounded by a circlet or collar. From the foot or bottom of the cross is suspended an ornament. The cross bearing these ornaments

tions is attached to and hangs pendent from an ordinary pin and bar. The back of the cross is a flat surface, the white and shaded lines in drawing indicating ornamental surface, the horns from the head retreating at the top somewhat over the circlet or collar. The collar and head are firmly secured to the cross.

I claim—

The design for badges, pins, and charms of the pattern and shape herein shown, consisting of an ornament representing a Maltese cross bearing an elk's head encircled by a collar, and having at the foot of the cross, pendent, an ornament, the cross from its upper arm attached to and pendent from an ordinary pin and bar, all as described, and shown in the drawing.

CHARLES G. MALLIET.
